UNITED STATES PATENT OFFICE.

EDWARD ERMOLD, OF NEW YORK, N. Y.

BOTTLE-LABELING MACHINE.

Application filed February 6, 1925. Serial No. 7,299.

To all whom it may concern:

Be it known that I, EDWARD ERMOLD, a citizen of the United States, and a resident of New York city, in the county of New York and State of New York, have invented certain new and useful Improvements in Bottle-Labeling Machines, of which the following is a specification.

This invention relates to improvements in machines for applying labels to bottles and comprises improvements upon the machine set forth in my Patent No. 1,023,143, dated April 16, 1912.

The present invention embodies an improved mechanism for applying lead or aluminum foil to the neck of the bottle in addition to the labels applied to the neck and body portion thereof.

In the present instance the invention is to be described in connection with my former patent, above referred to, although the invention is applicable to other types of machines of this class.

In the drawings:

Figure 1 is a central section of the improved mechanism, showing the frame and label boxes in elevation.

Figure 2 is a front elevation of the parts shown in Figure 1, portions of the frame and label boxes being omitted.

Figure 3 is a fragmentary view showing the foil bent downward as the same is held in position on the neck of the bottle by the presser arm or grip finger.

Figures 4 and 5 are fragmentary views showing succeeding positions of the operating parts from that shown in Figures 1 and 3.

Figures 6 and 7 are longitudinal and transverse sectional views, on an enlarged scale, of the foil presser foot, of the presser arm or grip finger.

Figure 8 is a section on line 8—8 of Figure 2.

Referring to the drawings, the different operative parts, not to be described, are similar and operate in the same manner as shown and described in my above referred to patent. In the present instance and in accordance with the present invention, the frame 1 supports upon suitable rods 25 secured thereto, suitable body and neck label boxes for holding respectively neck labels 44 and body labels 43. In addition to the neck and body label boxes, a similar box 2 is provided on the extended ends of the rods

25, for holding a pile of very thin sheets of lead, tin or aluminum foil 3.

Suitable pickers 52 are provided for simultaneously removing from the label and foil boxes a body label, a neck label and a neck foil, and transferring the same to the bottle to be labeled on a bottle rest 22, in which position the parts are shown in Figures 1 and 2. A presser arm or grip finger 86 is provided for holding the labels and foil in position on the bottle after the same are brought into position over the bottle, as clearly shown in Figures 1 and 2, the action and operation of the pickers and grip finger being similar to that described in my above referred to patent.

In the present instance and in accordance with the present invention the outer end of the grip finger is provided with a foil presser finger 5 in addition to the label presser fingers 87 and 88. The foil presser finger 5 is connected to one end of a bar 6 slidably mounted in the end of the grip finger 86 to which it is also connected by means of a spring 7 which acts to cushion the pressing movement of the presser finger 5. The presser finger 5 is provided with a longitudinal bore 8 closed at one end which terminates in a plurality of spaced, downwardly extending, passageways 9 situated on both sides of the presser finger 5, as shown in Figures 6 and 7. The open end of the bore 8 is connected to one end of a pipe 10 which passes through a slide 11 secured to the arm of the grip finger 86. The free end of the pipe 10 is connected to one end of a flexible hose 12 the other end of which is connected to an air motor, not shown, which is mounted in the frame of the machine.

Air under pressure continually passing down through the passageways 9 acts to blow or bend the foil 3 downward into the position shown in Figure 3 as soon as the pickers 52, in the operation of the machine, have moved upward from the position shown in Figures 1 and 2. If air pressure was not applied to the foil 3 the same would stay in a horizontal plane or bend upward at both ends after being released by the pickers, making it impossible for the wipers, presently to be described, to wipe the foil about the neck of the bottle. The neck and body labels 44 and 43 made of paper bend downward after being released by the pickers without the use of pressure

of any kind, and are easily wiped upon the bottle, however this condition does not exist in the case of metal foil which is relatively very stiff and difficult to handle, being 5 easily torn and crumpled.

Three pairs of wipers are employed, one pair for wiping the body labels on the body of the bottle, a second pair for wiping the neck labels on the neck of the bottle, and a 10 third pair for wiping the metal foil on the neck of the bottle.

The wipers for the metal foil comprise, in the present instance, and in accordance with the present invention soft flexible sponge 15 rubber rollers 14 rotatably mounted in holders 15 held in hubs 16 of bent arms 17 pivotally mounted at 18 to curved arms 19. The bent arms 17 are provided at their lower ends with rollers 20 which are arranged to 20 engage beveled cams 21. The bent arms 17 and the curved arms 19 are provided with stops 23 and 24, suitable springs 26 being provided for flexibly connecting the ends of the curved arms 19 with the upper parts of 25 the bent arms 17. The curved arms 19 are secured to the lower ends of rods 27 the upper ends of which are adjustably held in arms 28 mounted on short shafts 29 which are secured in arms 30 at one end of long 30 sleeves 31 mounted on stud shafts 32. The other ends of sleeves 31 have arms 33 connected by links 34 to a slide plate 117 which is operated by means shown and described in my former patent previously referred to.

35 The arms 30 and 35 are integral, arm 35 having a boss at its upper end in which is held stud 36 on which is pivotally mounted wiper holders 37 having adjustably fixed 40 flexible rubber wipers 109 and 135. The holders 37 have two downwardly projecting arms 38 and 39 the arms 38 having stops 40 acting against one side of the arms 30, the other arms 39 being connected to one end of 45 springs 41, the other ends of which are connected to arms 42 which are made integral with sleeves 31.

The wiping devices are thus loosely mounted and under spring tension to allow for a wiping action. As a yoke frame 112, 50 upon which the wiper mechanism just described is mounted, moves downward sleeves 31 are slightly rotated by the downward movement of slide 117 bringing arms 30 into the position shown in Figure 4, consequently 55 moving the rollers 14 toward the downwardly extending ends of the air blown metal foil 3, a further downward movement of the yoke frame 112 brings rollers 20 into contact with the beveled cams 21 and as the 60 rollers 20 ride on the beveled cams 21 arms 17 are moved about pivots 18 bringing wiping rollers 14 into contact with end of foil 3, wiping same around neck of bottle as shown in Fig. 5. The downward movement 65 of frame 112 is continuous throughout the

above described operation. It is to be noted that the wiper mechanism supporting one of the wiping rollers 14 is suitably adjusted to act on the metal foil before the other, so as to bring one end of the metal foil in 70 place on the neck of the bottle so that the other wiping roller which follows will wipe the other end of the metal foil over it as shown in Figure 5. As the rollers 20 leave the undersides of the beveled cams 21 the 75 arms 17 are brought back into the position shown in Figure 2 by the action of the springs 26.

The yoke frame 112 is moved up and down through means not shown, but shown 80 and described in my former patent above referred to.

From the above description it will be seen that means are provided, in addition to the ordinary means for applying paper neck and 85 body labels, means for applying metal foil, a material much more difficult to handle as it is easily torn or crumpled.

It will be seen that air under pressure applied to the foil presser foot immediately 90 acts to blow the ends of the metal foil downward, as soon as the foil presser foot has engaged the metal foil to hold it in place on the bottle, while the pickers move upward to receive another coating of paste and another set of labels and sheet of metal foil.

The soft flexible sponge rubber rollers act to gently press the ends of the metal foil about the neck of the bottle without tearing or crumpling the same, as any direct wiping 100 action is very apt to tear the metal foil and this is to be avoided.

While the invention has been described with particular reference to the details of construction, and in connection with my former patent above referred to, the same is not to be considered as limited thereto, as many changes can be made and still fall within the scope of the invention set forth in the following claims.

What I claim is:

1. A labeling machine comprising in combination, a rest to support a bottle or the like to be labeled, a metal foil box arranged above said rest, pickers for transferring sheets of metal foil from said box to articles on said rest, a grip finger for holding said metal foil on said article to be labeled, means on said grip finger for applying air under pressure to the ends of said metal foil to blow the same downward, and means for applying said metal foil to the article to be labeled.

2. A labeling machine comprising in combination, a rest to support a bottle or the like to be labeled, a metal foil box arranged above said rest, pickers for transferring sheets of metal foil from said box to articles on said rest, a grip finger for holding said metal foil on said article to be labeled, means

115

120

125

130

on said grip finger for applying air under pressure to the ends of said metal foil to blow the same downward, and means comprising soft flexible sponge rubber rollers for applying said metal foil to the article to be labeled.

3. A labeling machine comprising in combination, a rest to support a bottle or the like to be labeled, a metal foil box arranged above said rest, pickers for transferring sheets of metal foil from said box to articles on said rest, a grip finger for holding said metal foil on said article to be labeled, means on said grip finger comprising a plurality of oppositely opposed downwardly extending passageways for applying air under pressure to the ends of said metal foil to blow the same downward, and means for applying said metal foil to the article to be labeled.

4. A labeling machine comprising in combination, a rest to support a bottle or the like to be labeled, a metal foil box arranged above said rest, pickers for transferring sheets of metal foil from said box to articles on said rest, a grip finger for holding said metal foil on said article to be labeled, means on said grip finger comprising a central bore terminating in a plurality of oppositely opposed downwardly extending passageways for applying air uniformly under pressure to the ends of said metal foil to blow the same downward, and means comprising soft flexible sponge rubber rollers for applying said metal foil to the article to be labeled.

5. A labeling machine comprising in combination, a rest to support a bottle or the like to be labeled, a metal foil box arranged above said rest, pickers for transferring sheets of metal foil from said box to articles

on said rest, a grip finger for holding said metal foil on said article to be labeled, air passageways extending downwardly on opposite sides of said grip finger, flexible means for applying air under pressure to said passageways to blow the ends of said metal foil downward, and means for applying said metal foil to the article to be labeled.

6. A labeling machine comprising in combination, a rest to support a bottle or the like to be labeled, a metal foil box arranged above said rest, pickers for transferring sheets of metal foil from said box to articles on said rest, a grip finger for holding said metal foil on said article to be labeled, means for applying air under pressure to the ends of said metal foil held by said grip finger to blow the ends of said metal foil downward, and means for applying said metal foil to the article to be labeled.

7. A labeling machine comprising in combination, a rest to support a bottle or the like to be labeled, a metal foil box arranged above said rest, pickers for transferring sheets of metal foil from said box to articles on said rest, a grip finger for holding said metal foil on said article to be labeled, means for bending the ends of said metal foil held by said grip finger downward, and means for applying said metal foil to the article to be labeled.

In testimony whereof I have signed this specification in the presence of two subscribing witnesses.

EDWARD ERMOLD.
